UNITED STATES PATENT OFFICE.

ELIJAH D. CRAMER, OF YOUNGSTOWN, OHIO.

PENDULUM-LEVEL.

SPECIFICATION forming part of Letters Patent No. 313,290, dated March 3, 1885.

Application filed June 5, 1884. (No model.)

To all whom it may concern:

Be it known that I, ELIJAH D. CRAMER, a citizen of the United States, residing at Youngstown, in the county of Mahoning and State of Ohio, have invented certain new and useful Improvements in Masons' and Carpenters' Instruments; and I do hereby declare the following to be a full, clear, and exact description of my invention, such as will enable others skilled in the art to which it appertains to make and use the same, reference being had to the accompanying drawings, which form part of this specification.

My invention relates to that class of masons' and carpenters' instruments which are employed to obtain lines and angles; and its object is to provide a convenient instrument, which constitutes a plumb-level and protractor combined, by the use of which levels, angles, and perpendiculars may be readily found by the workman with perfect accuracy and under any circumstances. I attain this object by the mechanism hereinafter described, and illustrated in the drawings, in which—

Figure 1 is a view of the index or face side of the instrument in a horizontal position, and Fig. 2 is an edge sectional view of the same in the same position. Fig. 3 represents a view, partly in perspective, showing the interior of the device.

Similar letters refer to similar parts in all the figures.

The body of the instrument is a rectangular timber, B', having its edges at perfect right angles, and being preferably, for ordinary uses, three feet in length, four inches in width, and one and one-quarter inch thick. The attachment A, which is for the purpose of obtaining levels, is a rectangular box formed by a bottom and four sides of metal and a cover of glass, and is sunk into the face side of the timber equidistant between its edges near one end, so that the glass cover is on a plane with the surface of the timber, and the edges of the timber and the sides of the box are parallel.

The box for the size of the instrument above designated is preferably ten inches long, one inch wide, and five-eighths of an inch deep. A thumb-screw penetrates from one edge of the timber to the box, which has a threaded hole in its side to receive it as a means of adjustment. Near the upper end of the box when

perpendicular, extending from the bottom to the cover opposite, is a pin, b, which passes through a pendulum-rod by a hole somewhat larger than the pin except at the center of the rod, so that the pendulum, being weighted near its lower end, and provided with a flat head a trifle smaller in breadth than the width, to maintain its position, freely oscillates right and left and backward and forward with the movement of the instrument. At the breadth center of the bottom of the box, near the lower end, is a mark, c, which the pointed lower end of the pendulum covers when the instrument is exactly perpendicular. The colors of the bottom of the box, the mark, and the pendulum are preferably in strong contrast, to enable the eye to note the position of the pendulum with greater readiness.

The attachment B is for the purpose of obtaining levels and angles, and is a semicircular box of metal covered with glass, the bottom of which is marked as a protractor, indicating, near the edge of the half-disk formed by the bottom, the degrees of a quarter-circle each side of a point directly below the center of the whole circle, immediately below which is suspended a pendulum, weighted and supported as already described for the pendulum in attachment A. The box, which for the size of the instrument already given is preferably six inches along the flat side and five-eighths inch deep, is embedded into the timber at its length center, so that its flat side is on a plane with the edge of the timber and its cover on a plane with the face side, by which adjustment, when the instrument is brought to a horizontal with its opposite edge downward, the pendulum will point to the lowest point on the bottom, and each variation of the position of the instrument from the horizontal will be indicated in degrees by the pendulum.

I do not limit myself to any particular size for my instrument, or any part thereof, nor to the device described to secure a free oscillation of the pendulums, for which purpose any efficient device may be employed.

As will be at once comprehended, this instrument readily shows levels, angles, and perpendiculars, and is very valuable to carpenters, masons, and other builders, both for its absolute accuracy and for the convenience

with which it may be used. It is especially useful in getting perpendiculars in a wind which disturbs the accuracy of the "plumb-line," and in keeping the proper angle in battering back walls, for which the instruments now used are defective. It is evident that it would be useful in surveying.

I am aware that a protractor without a pendulum for obtaining lines and angles is old, 10 and I do not claim such to be my invention.

What I do claim as my invention, and desire to secure by Letters Patent, is—

In an instrument for obtaining perpendiculars, the straight-edge or timber B', having a 15 rectangular box, A, with a transparent front,

the pivot-pin b, extending through the upper part of the said box, and enlarged at its center, as shown, and the pendulum mounted upon said pivot and adapted to swing laterally as well as back and forth, the instrument 20 being provided with a center-mark, c, to center the free end of the pendulum, substantially as specified.

In testimony whereof I have hereunto affixed my name and seal in the presence of two wit- 25 nesses.

ELIJAH D. CRAMER. [L. S.]
